ASYMMETRICAL COLD CATHODE
FLIP-FLOP CIRCUIT

Charles R. Williams, Hawthorne, and Glenn E. Hagen, Lawndale, Calif., assignors to Northrop Aircraft, Inc., Hawthorne, Calif., a corporation of California

Application June 12, 1950, Serial No. 167,572

6 Claims. (Cl. 315—337)

1

The present invention relates to cold cathode tube flip-flop circuits suitable for use in binary counters, and is an improvement on the flip-flop circuit shown, described, and claimed in the copending Hagen application, Serial No. 100,178, filed June 20, 1949, now Patent No. 2,575,559.

The term flip-flop as used herein defines a device which has two stable states and is capable of being triggered from one state to the other. A dual cold cathode gas tube flip-flop has two conducting stable states; either one cathode is conducting, or the other cathode is conducting. The tube is non-conducting only during relatively short transition times, and sufficient supply voltage is provided to insure reignition.

Circuits for use with dual cathode gas tubes to obtain flip-flop operation thereof have the following requirements broadly in common:

1. A supply voltage source higher than the firing voltage of the tube.
2. A current limiting resistance in series with the supply voltage.
3. A cathode circuit such that in either stable state the "on" cathode is at a higher positive potential than the "off" cathode.
4. A means of coupling in a triggering pulse which decreases the voltage across the tube and extinguishes the glow current.
5. A means of maintaining the "on" to "off" cathode differential voltage during the triggering transition time.
6. A means of delaying the rise of the voltage across the tube during triggering to allow ionization dissipation before refiring.

One form in which these components can be combined is shown, described, and claimed in the Hagen application cited above.

The fundamental Hagen circuit is symmetrical and in most instances output can be taken from one or the other of the cathodes, both such outputs being alike in wave form. The voltage output wave form on the cathodes is ideal for the control of relays, gates and indicators, for example, but is not entirely suitable for differentiation to form the most desirable type of carry pulse when the circuit is used in multi-stage binary counters. The advantages of the asymmetrical circuit of the present invention over the symmetrical circuit are (1) all of the above six requirements can be satisfied with fewer circuit components; (2) the cathode voltage wave form, where its use is desired, is doubled in amplitude.

It is an object of the present invention to provide a modified Hagen circuit operative to provide a suitable carry pulse.

It is another object of the invention to provide a binary counter using asymmetrical flip-flop circuits of the general Hagen type.

It is still another object of the present inven-

2

tion to provide a flip-flop circuit of the Hagen type having two distinct types of output wave forms available.

And it is a further object of the present invention to provide an asymmetrical flip-flop circuit of the general Hagen type.

Briefly, the present invention includes the use of a glow tube having an anode and two cathodes connected in a circuit where an input pulse will flip the discharge from one cathode to the other. One cathode is connected to fire a two electrode glow tube, such as a neon indicator lamp, and the other cathode is connected to a resistance-capacity (RC) circuit, as in the Hagen circuit described above.

During the flip-flop action of the circuit of the present invention, a sharp carry pulse is generated at one cathode as the two electrode glow tube connected thereto is fired, whereas a large, slower voltage swing can be obtained from the other cathode that is suitable for the control of relays, diode gates, etc.

The present invention will be more fully understood by reference to the drawings, in which:

25. Figure 1 is a side view in elevation of a tube suitable for use in the circuit of the present invention.

Figure 2 is a diagram of one form of asymmetrical flip-flop according to the present invention.

30. Figure 3 is a diagram of a modification of the circuit of Figure 1.

Figure 4 is a binary counter circuit using one form of asymmetrical flip-flop circuit of the present invention.

As shown in Figure 1, the tube preferred for use in all of the circuits of Figures 2 to 4 is provided with an envelope 1 containing an anode wire 2, flanked on each side by cathode wires 3 and 4. These wires pass through an external pinch 5 to form an anode lead 6 and cathode leads 7 and 8 respectively.

A preferred tube is one inch long by $\frac{1}{8}$ inch inside diameter. The gas pressure in the tube, and the anode to cathode spacing is adjusted to give a desirable firing to burning voltage differential. Electrode surface spacings of .030 inch in helium at 250 mm. Hg pressure are satisfactory, and cathode wires of .010 to .015 inch diameter, .1 inch long will satisfactorily carry up to 1.0 ma. current. Suitable tube currents for flip-flop operation range from 0.1 to 1.0 ma. Such a tube will provide usable "on" to "off" cathode differentials of from 50 to 150 volts. Burning voltages are about 150 to 200 volts and firing potentials are about 250 to 500 volts depending upon gas mixture, and material and condition of cathodes.

For long life and most dependable operation, we prefer that the tube have from one percent

to five percent of a recombinable polyatomic gas therein, such as hydrogen or water vapor, for example, in addition to the inert gas filling, in accordance with the teachings of another co-pending application, Serial No. 156,659, filed April 18, 1950. The anode area is not critical, and conduction usually occurs from relatively small area points on the anode surface. The anode is preferably placed centrally between the two cathodes to obtain symmetrical electrical characteristics and in the same plane with the cathodes for ease of manufacture. However, in the circuits of Figures 2, 3 and 4, the anode 2 is shown as entering the tube from the opposite end of the envelope from the cathodes, for ease of circuit illustration.

Referring next to Figure 2, anode 2 is connected to a source 7 of positive potential greater than the striking voltage of the tube through a limiting resistor 10. Anode 2 is also connected to an input line 11 through an input capacity 12, a diode 13 and a pulse generator 14 generating negative input pulses. The diode 13 is oriented to pass the negative pulses to the anode 2.

One cathode 4 is connected to the positive end of a constant voltage supply 15, and the other cathode 3 is connected to ground (and the negative end of source 7) through cathode resistor 16 paralleled by a cathode capacity 17.

In the operation of the circuit of Figure 2, first assume that there is a glow discharge between anode 2 and cathode 3. The current of the discharge flowing through limiting resistor 10 depresses the voltage of the source 7 sufficiently that the voltage difference between anode 2 and cathode 3 is only the burning voltage of the two. The current of the discharge flowing through cathode resistance 16 causes condenser 17 to be charged to a potential greater than supply voltage 15. If a negative pulse is applied at the anode 2 through the input diode 13 and condenser 12 combination, the glow discharge between anode 2 and cathode 3 will be interrupted, and the voltage at anode 2 will then rise toward the + value of source 7. Before the voltage at anode 2 reaches the source value, there will be a glow discharge again initiated between anode 2 and one of the cathodes 3 and 4. The cathode condenser 17, however, maintains the voltage at cathode 3 at a higher positive potential than the voltage at cathode 4. Thus, the glow discharge will be struck between anode 2 and cathode 4.

After the glow discharge has been initiated between cathode 4 and anode 2, assume that another negative pulse is applied at anode 2 through the input circuit 11. Again the glow discharge will be interrupted, and the rise of voltage at anode 2 toward the source voltage will be sufficient to restrike a glow discharge between anode 2 and cathodes 3 or 4. However, the condenser 17 is not charged, and the voltage at cathode 3 is lower than the voltage at cathode 4. Hence, the glow discharge will be struck between cathode 3 and anode 2. The diode 13 permits negative pulses to pass relatively unimpeded from pulse generator 14 to anode 2; yet prevents negative pulses generated at anode 2, by the restriking of the glow discharge, from being reflected back to pulse generator 14. During the period of glow discharge, when the potential of anode 2 is rising, diode 13 is in its conducting state permitting input condenser 12 to act to the full extent of its capacity in controlling

the anode 2 potential rise rate. This control of the rise rate obtains sufficient glow discharge interruption time to permit necessary deionization of the gas before restriking. The diode 13 also acts as an anti-oscillation device to compensate for oscillatory tendencies caused by the anode to cathode capacitance loading effect of the connection of input condenser 12 from anode 2 through pulse generator 14 to ground. This specific feature is shown described and claimed in our companion application, Serial No. 180,257, filed August 18, 1950.

In the modified circuit of Figure 3, the constant voltage source 15 is isolated from cathode 4 by a leak resistor 20; and cathode 4 is connected to ground through a two electrode glow tube 21 and a second constant voltage source 22; the voltage difference between the two sources being of a value equal to or slightly less than the burning voltage of the two electrode glow tube 21. The constant voltage source 22 is useful in adjusting the proper voltage to the two electrode glow tube 21, but a two electrode glow tube 21 can be selected to have its burning voltage close to the voltage difference between cathode 4 and ground. In this case, the second constant voltage supply can be dispensed with, as shown by dotted line 23. A satisfactory two electrode glow tube suitable for use in the circuits of Figures 3 and 4 (to be described later) is type NE2, manufactured by the General Electric Company and well known in the art.

The general operation of the circuit of Figure 3 is very similar to that of the device of Figure 2. When cathode 3 is conducting, the current flow through cathode resistor 16 raises the potential of cathode 3 to a value X, for example. The voltage of constant voltage supply 15 is made to be approximately one-half the magnitude of X. Leakage resistor 20 maintains the potential of cathode 4 at the value one-half X when cathode 4 is not conducting glow current. Sharp output pulses are taken off directly from cathode 4 through output line 24. These output pulses are positive pulses by nature of the characteristics of the glow tube 21 and are generated by the rapid firing thereof.

It is a well known property of gas and vapor tubes, in general, that very steep voltage wave fronts and high current pulses can be obtained from the firing of these tubes while under the stress of a high anode to cathode potential. Use is made of this property in the flip-flop tube 1 for the generation of carry pulses. When the tube 1 is triggered "off" the plate potential rises, until the tube refires, to a value of approximately 400 volts above the lowest cathode. Upon firing there is a very rapid drop in plate to "on" cathode voltage accompanied by a relatively high current surge through the tube. The carry pulses are derived from this voltage drop which may have a magnitude as high as 200 volts. Negative pulses can be coupled from the anode, or positive pulses can be derived from the cathodes. Taking pulses from one of the cathodes automatically accomplishes the one-half input rate division required for binary counting carry pulses.

In the case of the two electrode glow tube 21, such as the type NE2, the firing to burning potential drop is of the order of 20 volts if the voltage is applied relatively slowly (one millisecond). However, if the voltage is applied rapidly (one microsecond), then firing potentials as high as 150 volts can be obtained across the two electrode glow tube 21. The firing of the flip-flop tube 1

supplies this rapid rise to a two electrode glow tube 21 in its cathode circuit. The firing of the two electrode glow tube 21 rapidly drops its potential to its burning voltage of about 50 volts. Hence, very sharp positive pulses as high as 100 volts in amplitude can be obtained across the two electrode glow tube 21.

It should be noted further that even though the two electrode glow tube 21 is already conducting its exhibits considerable impedance to very sharp voltage changes. If constant supply voltage 15 is sufficient to maintain conduction in the two electrode glow tube 21, carry pulses will still be generated but they will be of diminished amplitude.

A second purpose of the glow tube 21 is that it indicates the binary state of the flip-flop and it indicates the total count of the binary counter.

A second output line 25 can be attached to cathode 3. This connection provides a wide but slow voltage swing suitable, as pointed out above, for the biasing of diodes or other switching devices.

The diagram of Figure 4 shows the circuit of Figure 3 as connected in a binary counter, which may have as many stages as desired.

Here the output line 24 from cathode 4 is connected through the leakage resistor 20 and the constant voltage supply 15 to ground. The output line 24 is also connected through a differentiating capacity 30 connected through an inverting diode 31 to ground. The input line 11a of a second stage S is connected to the junction of capacity 30 and diode 31.

In this circuit the pulses appearing in the output line 24 are positive and are bypassed through capacity 30 and diode 31 to ground, thereby charging condenser 30. When the positive pulse goes from its positive peak down to a normal voltage, the condenser 30 will tend to discharge through the now conducting two electrode glow tube 21, thereby establishing a negative pulse on the input diode 13a of the next stage S; this negative pulse being bypassed by input diode 13a to the anode of the next stage S, to trigger that stage.

As each stage of the binary counter shown in Figure 4 generates its own carry pulse, there is no limit to the number of stages that can be used. Further, the power consumption of each stage is very low so that the power consumption of a multi-stage binary counter is far lower than in the equivalent circuit using tubes that require cathode heating.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is, there-

fore, claimed in any of its forms or modifications within the legitimate and valid scope of the appended claims.

What is claimed is:

5. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a constant voltage supply in series with the other 10 of said cathodes and subtractive to the potential of said source, and an input line connected to apply an input pulse to said anode.
15. Apparatus in accordance with claim 1 wherein a two electrode glow tube is directly connected between the cathode connected to said constant voltage supply and said source, wherein a leak resistor is connected between said constant voltage supply and said connected cathode, and an output line connected to said latter cathode, the potential of said constant voltage supply being approximately the burning potential of said two electrode glow tube.
20. A binary counter comprising a plurality of flip-flop stages, according to claim 2, with the 25 output line of the one stage connected to the input line of the next stage through a pulse inversion means.
25. A binary counter comprising a plurality of flip-flop stages, according to claim 2, with the 30 output line of one stage connected to the input line of the next stage through a pulse inversion means, said means including a series capacity and a rectifier across said output.
35. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode.
40. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode, said output line including a pulse inversion network.
45. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode, said output line including a pulse inversion network.
50. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode.
55. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode, said output line including a pulse inversion network.
60. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode, said output line including a pulse inversion network.
65. A flip-flop circuit including a tube comprising an envelope, a pair of cold cathodes and an intermediate anode in said envelope, a filling of gas at glow discharge pressure in said envelope, a limiting resistance, a source of potential higher than the firing potential of said tube connected between said anode and both of said cathodes in series with said limiting resistance, an RC circuit connected to one of said cathodes, a two electrode glow tube connected between said source and the other of said cathodes, an input line connected to apply an input pulse to said anode, and an output line connected to the last mentioned cathode, said output line including a pulse inversion network.
